T. SCHISGALL.
ATTACHMENT FOR CLOCKS.
APPLICATION FILED OCT. 29, 1917.

1,267,807.

Patented May 28, 1918.

UNITED STATES PATENT OFFICE.

THEODORE SCHISGALL, OF NEW YORK, N. Y., ASSIGNOR TO TRAVELIGHT MFG. CO., OF PHILADELPHIA, PENNSYLVANIA, A CORPORATION OF DELAWARE.

ATTACHMENT FOR CLOCKS.

1,267,807.

Specification of Letters Patent. Patented May 28, 1918.

Application filed October 29, 1917. Serial No. 198,937.

To all whom it may concern:

Be it known that I, THEODORE SCHISGALL, a citizen of the United States, residing in the city, county, and State of New York, 5 have invented a new and useful Attachment for Clocks, of which the following is a specification.

My invention consists of an amusement attachment for a clock or other motor embodying a figure on the body of the clock, the same having a head with openings therein for the appearance therethrough of the representations of human eyes, and a tongue, said eyes being formed on a sheet or plate to 10 which is attached a hanger and stiffener therefor, said tongue being a member of said hanger, vibrating motions being imparted to said hanger and plate by the train of gearing of the clock whereby motions are 15 imparted to the eyes and tongue, thus producing an attractive amusement.

Figure 1 represents a perspective view of an amusement attachment for a clock including the body of the latter embodying 20 my invention.

Fig. 2 represents a rear view of said attachment and the interior of the box.

Fig. 3 represents a vertical section on line 3-3 Fig. 2.

30 Fig. 4 represents an elevation of certain members of the clock mechanism or train of gearing of the clock.

Fig. 5 represents a front elevation of the representation of the eyes and the tongue, 35 and the plate on which the same exists on enlarged scales.

Similar numerals of reference indicate corresponding parts in the figures.

Referring to the drawings,

40 1 designates the train of gearing of a clock, and 2 designates the case therefor. 3 designates the escapement lever of said train, the same having attached to its axis 4 the arm 5 which is jointed as at 6 to another arm 7 above the same, said arm 7 being adapted to move as a pendulum the arm 5 rising from said lever, and being adapted to receive oscillating motions therefrom, and impart the same to said arm 7.

45 Mounted on the clock case is the column or upright piece 8 which is of the form of a figure, in the present instance of Santa Claus, the back of the same having thereon the vertically-extending recess 9 in which 50 said levers 5 and 7 are adapted to oscillate.

In the head 10 of the figure are openings 11 simulating eye-sockets, back of which are representations of eye-balls 12 which are formed on the plate or sheet 13, to which latter is secured the hanger 14 composed of 60 a strip of metal or other suitable material, which while serving to stiffen said plate has in its upper end the opening 15 which is adapted to be fitted on the pin 16 of the form of an elbow, the vertical limb of which is 65 driven into the adjacent portion of the head, said pin thus comprising an axis for said hanger and consequently for said plate, it being noticed that the upper end of the arm 7 is secured to said hanger, whereby the latter 70 receives oscillations, in the present case, to the right and left, it being noticed also that the back of the head has therein the recess 17, wherein said plate 13 is adapted to have 75 its play.

In the lower portion of said head is the opening 18 which simulates open lips of the figure, and in which is freely received the tongue 19 which simulates a human tongue, and is composed of the lower portion of the 80 hanger 14 bent out forwardly therefrom and adapted to occupy said opening 18, it being of less width than the latter, so as to be capable of oscillating to the right and left 85 therein.

It will be seen that when the clock is running, oscillating motions are imparted to the arms 5 and 7, and consequently to the plate 13, the latter thus moving the eye balls to the right and left behind the sockets 11, and 90 also moving the tongue 19 to the right and left in the open lips 18, thus producing an attractive and amusing attachment for the clock.

Of course, any train of gearing may be 95 employed to operate the movable members of the attachment through the medium of the arms 5 and 7, without necessarily limiting the same to a clock.

Owing to the jointed arms 5 and 7, the 100 axis of the escapement lever imparts the proper throw to the former to cause the plate 13 to oscillate quickly and also to a short extent, whereby the simulations of the eye balls play within the width of the simulations of the eye sockets without being covered by the latter. The tongue also moves quickly and oscillates to a short extent in the lips 18 avoiding widening of the latter.

Having thus described my invention what 110

I claim as new and desire to secure by Letters Patent, is:—

1. A figure provided with a head having therein openings simulating eye sockets, a plate adapted to be mounted on said head back of said eye-sockets, said plate having therein simulations of eye balls, a mechanically operated motor, and jointed levers connected with each other and respectively with said plate and a member of said motor whereby short oscillations are imparted to said plate and consequently to said eye balls.
2. A figure provided with a plate having therein simulations of eye balls, a head having therein openings simulating open lips, a hanger mounted on said head back of said lips, said hanger having thereon the simulation of a tongue which latter is adapted to occupy and play in said lips, said hanger being adapted to stiffen said plate and to form means for the suspension of the plate in said head, a mechanically operated motor, and a connection for said hanger, and a movable member of said motor, whereby oscillations are imparted to said hanger and consequently to said tongue.
3. A figure provided with a head having therein openings simulating eye sockets, and open lips, an oscillating hanger mounted on said figure back of said head, a plate carried by said hanger having simulations of eye balls, a tongue on said hanger adapted to play in said lips, said hanger being adapted to stiffen said plate and to form means for

the suspension of the plate on said head, and jointed levers forming a connection with said hanger, and a movable member of a train of gearing adapted to oscillate said hanger and consequently said plate and tongue.

4. An upright piece provided with a head having therein openings simulating eye-sockets and open lips, a plate back of said head, a hanger mounted on said head and adapted to carry said plate and stiffen the same, said plate having thereon simulations of eye balls, and said hanger having connected therewith a tongue which is adapted to enter said lips, a mechanically operated motor, and a connection for said hanger and a movable member of said motor, said connection being formed of jointed arms.

5. A figure provided with a head having therein openings simulating eye-sockets and open lips, a hanger mounted on said head back of said openings, a plate secured to said hanger having on its front face simulations of eye balls, a simulation of a tongue on said hanger adapted to play in said lips, and a mechanically operated motor having a movable member adapted to be connected with said hanger for oscillating the latter and said tongue.

THEODORE SCHISGALL.
